UNITED STATES PATENT OFFICE.

RICHARD I. JONES, OF TOPEKA, KANSAS.

SEWERAGE SYSTEM.

1,261,401.

Specification of Letters Patent.

Patented Apr. 2, 1918.

Application filed September 14, 1916. Serial No. 120,123.

To all whom it may concern:

Be it known that I, RICHARD I. JONES, a citizen of the United States, residing at Topeka, in the county of Shawnee and State of 5 Kansas, have invented new and useful Improvements in Sewerage Systems, of which the following is a specification, full, clear, and exact within the meaning of the patent statutes.

10 My invention relates to new and useful improvements in sewerage systems, and has for its object the provision of novel mechanism for the reception and drainage of waste water from houses, barns, and the 15 like, to be utilized to flush water-closet bowls. In other words, the idea comprehended by my invention is the utilization of waste water from houses, barns, etc., for the economical flushing of water-closets, the 20 supply of such water to the closet being from a storage reservoir, which, in turn, is supplied, by gravity, as from a catch-basin, into which rain water, or waste water from a kitchen sink, may flow, the flow of water 25 to the closet-bowl being controlled by an automatically opening and closing valve, which, also, may be manually opened.

Subsidiary objects of improvement in structural parts, going to make up the ultimate 30 perfection of the entire device, will appear as the specification proceeds and the nature of the invention more fully appears.

With these objects in view, the invention comprehends the novel construction, combination and arrangement of parts of a drainage and sewerage system, as will be fully described in the specification, emphasized in the claim, and illustrated in the drawing.

In the accompanying drawing, forming 40 part of my specifications, and in which like reference-characters denote corresponding parts throughout the several views, I have illustrated a form of apparatus capable of carrying out the underlying principles of the invention. The several figures of the drawing may be briefly described as follows:

Figure 1 is a view in side elevation, partly in section, of my apparatus, and

Fig. 2 is a fragmentary detail view of the 50 storage reservoir and of the float contained therewithin.

Referring, now, in detail to the drawing:

1 designates a vertical sewerage pipe sunk into the ground A, the top of the pipe projecting suitably above the ground, and having the usual water-closet seat 2 and cover 3

to close the opening 4 in the seat. The bottom of the pipe 1 may communicate with an underlying, vertically-aligned closet-bowl 5 communicating, in turn, with a sewer pipe 6, 60 having a water-seal or trap 7, leading the waste and water to the sewer or final outlet.

In parallelism and, by preference, in proximity with the pipe 1 is a vertical stand-pipe 8, also suitably projecting above the 65 ground A, and having its lower end disposed, preferably, near the top of the closet-bowl 5.

The lower end of the stand-pipe 8 is preferably seated in a base member, in this instance a block 9, desirably of Portland cement, having, in its top, a hemispherical socket 10, constituting a valve-seat. An inclined port 11 leads from the bottom of the valve-seat through the block 9, and, communicating with the lower end of said port and with said closet bowl, is an inclined pipe 12. Adapted to close passage through the port 11 is a valve 13, preferably, as shown, a ball-valve having a vertical valve-stem 14 70 extending through the top of the stand-pipe 8, and having its exteriorly-projecting end suitably articulated with a vertical link 15 pivotally connected, at its upper end, with a lever 16 fulcrumed, as at 17, to a suitable 75 support 18, the other end of said lever being pivotally connected with a depending pull-rod 19 carrying, at its free extremity, a handle 20 in convenient reach of a person using the closet. 80

Mounted for limited vertical movement on the valve-stem 14 is a hollow float 21, which is, preferably, in the form of a metallic cylinder. Advantageously, the float 21 is constructed with an integral tube 22 85 through its longitudinal center, through which the valve-stem 14 projects. 90

Suitable means for limiting the range of movement of the float 21 longitudinally of the valve-stem 14 are provided, and, in this 100 instance, comprise two disks 23, 23, co-operating with two pins 24 removably disposed in any two of a series of holes 25 in the valve-stem 14. By changing the position of these two pins 24 in the holes 25, so that 105 they are nearer to or farther away from each other, the range of movement of the float will be lessened or increased, as the case may be, in an obvious manner. If desired, of course, the disks 23, 23 may be 110 omitted, as the pins 24, in themselves, answer the purpose in view.

Communicating with the stand-pipe 8, near the bottom thereof, is an inclined pipe 25, whose upper end communicates with a catch-basin 26, which may have its top level 5 with the surface of the ground A, or may be disposed above the same. The catch-basin 26 may be disposed in a convenient place to pour waste water therein, or to run roof-water therein, or may connect with 10 kitchen-sinks to receive waste-water therefrom.

In use, it will be seen that the stand-pipe 14 constitutes a storage-reservoir for the waste water, which is supplied through pipe 15 25, and that, as soon as the float 21 reaches the top pin 24, further movement of the float, independent of the valve-stem 14, will cease, and the float will operate automatically to lift the valve-stem to unseat the 20 valve 13, permitting water from the reservoir to flow through the port 11 to the pipe 12, and thence to the closet-bowl 5, thereby flushing the same. Also, when desired, the valve 13 may be opened, independently of 25 the float 21, by pulling downward upon the pull-rod 19.

It will be obvious that the utility of my invention resides in the utilization of waste water to flush closet-bowls, and that the invention is of special value in places where water under pressure is not obtainable, as from a city water-main; but it is also obvious that, irrespective of water or not water under pressure may be obtained, my 30 invention is of value and utility, since it presents a very economical manner of use 35 of water, since purely waste water, as rain water from the roof of a dwelling house,

barn, or the like, or waste-water from kitchen-sinks, or the like, may be used to 40 supply the reservoir. In other words, my invention contemplates a novel system for the useful and economical disposition of waste water and its drainage, to flush water-closet bowls, and avoids freezing. 45

Having thus fully described my invention, what I claim as new and desire to secure by Letters Patent of the United States is:

In sewerage apparatus, the combination, 50 with a vertical water-closet pipe adapted to be sunk into the earth or ground, with its top projecting thereabove, and having a water-closet seat at its top and a water-closet bowl at its bottom, of a vertical stand-pipe, constituting a water-reservoir, disposed adjacent the water-closet pipe, and also projecting above the ground, a cement-block in which is seated the lower end of 55 said stand-pipe, said cement-block having a valve-seat in its top and an inclined port leading therefrom to the exterior thereof, an inclined pipe communicating with said port and with said bowl, a valve seatable on 60 said valve-seat and having a valve-stem projecting vertically through said stand-pipe, a float having limited longitudinal movement on said stem, an inclined pipe communicating with said stand-pipe near the bottom thereof, and a catch-basin communicating with said last mentioned inclined pipe at its other end. 65

In testimony whereof, I hereunto affix my signature.

RICHARD I. JONES.
